UNITED STATES PATENT OFFICE.

ANTON SCHOLZ, OF GARDNER, MASSACHUSETTS, ASSIGNOR TO FRANK W. SMITH COMPANY, OF GARDNER, MASSACHUSETTS, A CORPORATION OF MASSACHUSETTS.

DESIGN FOR A HANDLE FOR SPOONS OR FORKS.

41,695.

Specification for Design.

Patented Aug. 22, 1911.

Application filed August 11, 1910. Serial No. 576,779. Term of patent 3½ years.

To all whom it may concern:

Be it known that I, ANTON SCHOLZ, a citizen of the United States, residing at Gardner, in the county of Worcester and Commonwealth of Massachusetts, have invented a new, original, and ornamental Design for a Handle for Spoons or Forks, of which the following is a specification, reference being had to the accompanying drawing, forming part thereof.

The figure is a plan view of a spoon showing my new design applied to the handle.

I claim,

The ornamental design for a handle for spoons or forks, as shown.

Dated this fifth day of August, 1910.

ANTON SCHOLZ.
